Standard Sanitary Corporation, New York,
N. Y., a corporation of Delaware

Application July 31, 1937, Serial No. 156,689

12 Claims. (Cl. 257—141)

This invention relates to heat exchangers, and to thermal systems in which the heat exchangers are incorporated.

In particular the invention relates to heat exchangers of the radiant convector type, and to thermal systems wherein such heat exchangers are supplied with a fluid heating medium or a fluid cooling medium within the confines of fluid flow passages.

10 An outstanding feature of heat exchangers of the above type following principles of the present invention, is the cooperative association of a radiant convector having relatively low thermal conductivity, with a radiant convector having relatively high thermal conductivity. The association is advantageously such that the former radiant convector serves to initiate and direct flow of air over and in intimate contact with the heat exchange surfaces of the latter, the associated radiant convectors preferably forming a structurally compact heat exchange unit.

Preferably, a plurality of air-flow passages are provided in the radiant convector of low thermal conductivity; these being long as compared with 25 air-flow passages provided in the other radiant convector, and preferably vertically disposed for function as stacks in directing air flow. The radiant convector of high thermal conductivity is desirably formed with extensive heat transfer surfaces. It is advantageously located in the direct line of air flow from the above described stacks extending substantially horizontally across the collective stack openings. Preferably it is located intermediate the vertical extent of the 30 radiant convector of low thermal conductivity, intercepting the air-flow passages, i. e., stacks.

It is desirable that the radiant convector of low thermal conductivity be cast from iron, preferably in the form of similar sections, which, when 40 joined, collectively provide substantially plane outer faces adapting the heat exchange unit for radiant heating per se in addition to convection heating.

The radiant convector of high thermal conductivity is desirably of copper or of a copper alloy provided with extended fins affording a considerable area of heat exchange surface.

50 The thermal system of the invention provides for the supply of a fluid heating medium such as hot water or steam to both the radiant convectors of the heat exchange unit or units whenever appropriate, regulation of supply being had by suitable valves.

55 Convection currents of air are readily engendered by the radiant cast iron, thereby effecting

air flow upwardly through the stacks, passing over and in intimate contact with the heat exchange surfaces of the copper radiant convector. Since the relatively high thermal conductivity of copper imparts great capacity for thermal interchange, the above described combination is particularly effective and efficient for the thermal treatment and circulation of air. Once circulation through the thermal unit is initiated, the copper radiant convector functions as a primary circulator, boosting the velocity of circulation proportionally to the rate of heat interchange.

When appropriate, supply of heating fluid to the radiant convectors may be cut off and by 15 proper valve regulation, supply of cooling fluid may be effected solely to the convector of high thermal conductivity, i. e., the copper convector.

By suitable provided instrumentalities, the flow of a forced supply of air, conditioned or otherwise, may be directed over the heat exchange surfaces of the convector of high thermal conductivity intimately contacting such heat exchange surfaces in effecting heat transference therebetween, and, in the case of heat interchange from the surfaces to the flowing air, enhancing the rate of air circulation. Such forced supply of air is effective to provide superheating when desired and is essential for the promotion of air circulation when the heat exchange unit is used for 30 cooling. As an additional feature, such forced supply of air may be employed merely for circulating air in the room or other enclosure in which such heat interchange unit is located, without thermal treatment, when the normal 35 temperature of the room air is as desired. Under such conditions, of course, neither heating nor cooling fluid will be supplied to the radiant convectors. They remain dormant.

Provision may be made, preferably adjacent the 40 location of discharge from the heat exchange unit of the thermally treated or merely circulated air, for the admixture of fresh atmospheric air as and when desired.

Embodiments of the invention pursuant to the 45 structural characteristics generically outlined above afford a substantially complete range of thermal treatment for air, being particularly advantageous for use in hotels, apartments, or other buildings presenting a multitude of rooms whose 50 space is at a premium. Heating, cooling, and ventilating are accomplished as and when required through heat exchange units which are individually all inclusive and dimensionally compact.

In the drawings:

Fig. 1 represents a front elevation of a preferred embodiment of the heat exchange unit of the present invention. Portions of the front wall are broken out revealing portions of the internal structure in section;

Fig. 2 represents a horizontal section taken on the line 2—2 of Fig. 1;

Fig. 3 represents a vertical section taken on the line 3—3 of Fig. 1;

Fig. 4 represents a vertical section taken on the line 4—4 of Fig. 1;

Fig. 5 illustrates several of the heat exchange units of Fig. 1 incorporated in a preferred embodiment of the thermal system of the present invention;

Fig. 6 is a view similar to that of Fig. 1, but illustrating a slightly different embodiment of the invention;

Fig. 7 represents a fragmentary vertical section taken on the line 7—7 of Fig. 6; and

Fig. 8 is a view similar to Fig. 7, but illustrating a slightly different arrangement of parts.

Referring to the drawings, and particularly to Figs. 1 through 4:—the heat exchange unit of Fig. 1 comprises a radiant convector of relatively low thermal conductivity associated with a radiant convector of relatively high thermal conductivity, the former being indicated by the numeral 10, and the latter by the numeral 11.

The radiant convector 10 is, in the present instance, assembled from cast iron sections. Those intermediately located in the assembly, and similarly configurated for mutual joinder, are designated 12. Those serving to cap the ends are each configurated on one lateral side for joinder with the assembled intermediate units 12, and on the other lateral side for completing the external configuration of the heat exchange unit per se. They are designated 13 and 14, respectively.

The intermediate sections 12 are substantially I shape and hollow, see Fig. 2, providing passages 15 for the flow of a fluid heating medium. Their front and rear end faces are preferably plane as illustrated, having complementary formations at their edges. Such complementary formations may take the form of tongues and grooves, the tongues of one section, on assembly of the sections, interlocking with the grooves of the adjacent sections to form overlap joints 12a. Continuity of front and rear facing of the heat exchange unit is provided by the collective extents of the front and rear faces of the assembled sections. Exterior facial continuity is desirable from the standpoint of appearance, affording a "panel" surface which may be finished by application of a decorative coating material. The "panel" nature of the surface provides for radiant heating by the unit, supplementary to its primary convection heating.

The I shape of sections 12 provides lateral reentrant portions which cooperate, upon assembly of the sections, to form air-flow passages 16, extending vertically through the heat exchange unit in the form of stacks. Such passages are bounded by the heat exchange surfaces of the sections, a plurality of vertical ribs 12b being desirably formed integral with the stated surfaces and extending therefrom into the flow passages 16 for adding to the normal heat exchange surface of the passage walls.

The end sections 13 and 14 are formed longer than are the intermediate sections 12. Each has one lateral wall configurated similarly to

the lateral configuration of a section 12 for co-operation therewith in forming an air-flow passage 16, but has the other lateral walls planar, as illustrated, for completing the external contour of the heat exchange unit.

The intermediate sections 12 are united side by side in vertical coextension, preferably by means of sleeves 17 fitting into suitable registering apertures of contiguous sections. The longer end sections 13 and 14 are united to the assembled intermediate sections 12 also by means of sleeves 17, but are so disposed vertically with respect to such intermediate sections and to each other as to form bottom extensions 13a and 14a, respectively, serving as feet for the heat exchange unit, and top extensions 13b and 14b, respectively, serving to receive suitable air outlet means, hereinafter described. Elevation of the intermediate sections from the surface supporting the heat exchange unit, accomplished by means of the feet 13a and 14a, provides a bottom air inlet opening 18, see Fig. 1, extending transversely of the unit and leading to the air-flow passages, i. e., stacks 16.

A cover element 10—1, preferably of sheet metal, shaped to finish the uppermost portion of the unit in accord with the plane face, box-like contour of the remainder, and to provide a reentrant, air-directing baffle 10—1a, may be applied to the top of the unit, see particularly Figs. 3 and 4.

The opening at the front of the unit of the throat formed by baffle 10—1a may be concealed by an ornamental grill 10—2.

The passages 15 formed by the hollow sections 12, and the corresponding passages formed by the hollow end sections 13 and 14, communicate with one another through the sleeves 17 to afford circulation of a supplied fluid heating medium through the hollow interior of the cast iron radiant convector 10.

Generically, the radiant convector of relatively high thermal conductivity is associated with the radiant convector of relatively low thermal conductivity in such manner as to be located in the direct line of air flow through the air-flow passages of the latter. By positioning the former intermediate the vertical extent of the air-flow passages of the latter, full advantage of the stack effect of such air-flow passages is derived.

Accordingly, in the preferred embodiment illustrated, the radiant convector 11 is substantially centrally placed within the body of the radiant convector 10, extending transversely across the air-flow passages 16 thereof.

Such positioning of the radiant convector 11 is afforded by peripherally closed apertures 19 provided substantially centrally of each of the intermediate sections 12 and of each of the end sections 13 and 14. When the sections are assembled the apertures register to form a central passage 20 extending continuously horizontally through the body of the cast iron radiant convector 10 across the air-flow passages 16 thereof. Thus the air-flow passages 16 are divided into an upper and a lower set, spaced apart from each other.

The radiant convector 11 is advantageously formed of metal predominantly of copper content resulting in the relatively high thermal conductivity which characterizes it. A convenient construction for such copper radiant convector comprises a series of copper tubes 11a whose flow passages are interconnected by a flow-distributing header 11b, and a flow-receiving header 75

11c. The copper tubes are joined externally by a plurality of closely spaced copper plates 11d, providing extensive heat exchange surfaces and air-flow passages, numerous as compared to the 5 stacks 16.

The size of the copper radiant convector 11 relative to the size of the cast iron radiant convector 10 will vary according to the requirements of particular installations. It will, however, usually be small in comparison, and have 10 comparatively short air-flow passages. The dimensions and configuration of the apertures 19 will of course vary according to the size and configuration of radiant convector 11.

15 Support of the copper radiant convector 11 within the passage 20 may be accomplished incidentally by means of supply and return piping 21 and 22, respectively, forming part of the thermal system of the invention. Such piping 20 21, 22, communicates with the headers 11a and 11b, respectively, for effecting circulation of a fluid thermal medium through the copper tubes 11c.

25 A manually operable three-way valve 23, interposed in supply piping 21, regulates flow of the fluid heating medium to the cast iron radiant convector 10 by way of the short pipe connection 24. Return flow therefrom into return piping 22 passes through the short pipe connection 25 30 and the valve 26.

When the above described heat exchange unit is utilized for heating purposes, a suitable fluid heating medium, in the present instance hot water, is supplied to both of the radiant convectors 10 and 11, through supply piping 21. The heat exchange surfaces of the stacks 16 of radiant convector 10 thereupon initiate air-flow upwardly through the stacks over and in intimate contact with the heat exchange surfaces of radiant convector 11. The high thermal conductivity of radiant convector 11 accomplishes transfer of a considerable quantity of heat to the air flowing across its surfaces from stacks 16, and, accordingly, boosts the rate of air flow through the 40 unit. Thus, the cooperative combination of the two types of radiant convectors provides a peculiarly effective convector heater. In addition, radiant heating occurs from the exterior panel faces thereof.

50 The thermal system of the invention, utilizing to the full extent the advantages of the radiant convector combination of the heat exchange unit, provides for a substantially complete range of thermal treatment of air, inclusive of heating, 55 super-heating, and cooling, as well as for mere air circulation. A representative embodiment of the system is illustrated diagrammatically in Fig. 5.

60 Referring to Fig. 5, at 30a, 30b, and 30c, are indicated heat exchange units similar to that of Fig. 1, interconnected by suitable piping. The system may, of course, be extended as indicated by the broken endings of the piping, to include 65 any desired number of heat exchange units.

65 Apparatus for supplying a fluid heating medium, in the present case hot water, may comprise a conventional type boiler indicated at 31 and a water circulator 32. They may be connected by supply piping 33 and return piping 34 to the piping immediately serving the various heat exchange units, such piping with its included valves being indicated as heretofore with respect to Fig. 1.

A refrigerating and water cooling apparatus,

indicated diagrammatically at 35, is advantageously connected in the above described piping system by supply and return piping 36 and 37, respectively, suitable valves 38 and 39 and 38-1 and 39-1 being provided for cutting off either 5 the heating or the cooling apparatus while the other is in use.

When the heat exchange units are utilized for cooling, the valves 23, controlling supply of fluid thermal medium to the units, are adjusted to preclude flow into radiant convector 10 while directing flow to radiant convector 11; the valves 26 are adjusted to preclude back-flow into radiant convectors 10; and the valves 38-1 and 39-1 are closed to cut off the heating apparatus 21 from communication with the piping system. Circulation of cooling fluid from apparatus 35, thus takes place through radiant convectors 11 exclusively.

20 A suitable expansion tank (not shown) is provided in the thermal system in the usual manner, and a suitable auxiliary expansion tank (not shown) is connected, as by piping 31-1, with the heating apparatus per se, functioning during 25 the time such heating apparatus is cut off from the thermal system proper. Drain cocks (not shown) may be supplied at appropriate locations for removing fluid heating and/or cooling medium from the system.

30 For prompting circulation of air through the heat exchange unit during its use as an air cooler, means for supplying a forced draft of air is provided.

35 Such means advantageously comprises an air discharge tube 40 disposed directly under radiant convector 11, its length being substantially co-extensive with the length of such convector. The top of the tube may be perforated, the perforations, designated 41, functioning as nozzles for directing flow of air from the interior of the tube over and in intimate contact with the heat exchange surfaces of radiant convector 11.

40 Advantageously, with respect to the thermal system, see Fig. 5, compressed air is furnished 45 the air discharge tubes 40 of the units from a central supply of compressed air through suitable piping 42. An air compressor 43, which may be motivated, as illustrated, by a motor 44, is here arranged to discharge compressed air into a reservoir 45; the latter communicating directly with the supply piping 42. Desirably, the air is subjected to a conditioning treatment such as dehumidification and filtration in a suitable conditioning apparatus, indicated generally at 46, just 50 prior to compression.

55 The forced supply of air, conditioned or otherwise, may be effectively utilized when the heat exchange unit is functioning as a heater as well as when it is functioning as a cooler, or may be utilized merely for promoting air circulation in the room concerned.

60 Suitable well known thermostatic means may accomplish automatic control of heating, cooling, and air circulation according to existing 65 room temperature.

Referring now to Figs. 6 and 7 in which an additional optional feature of the invention is illustrated:—the heat exchange unit is essentially the same as that appearing in Fig. 1 with the addition of Venturi means adjacent the outlet opening of the unit for admixing fresh atmospheric air with the thermally treated air.

66 The Venturi means may take the form of tubes 50, each converging from an intake opening

(not shown) communicating with a source of exterior air, as for instance a window aperture, to a nozzle opening 50a disposed in the back of the air discharge throat which leads to the air outlet 10-2. Suitable valve means may be provided adjacent the intake opening for regulating the amount of fresh air drawn in.

The Venturi tubes 50 may penetrate the cover 10-1 of the unit at spaced locations, see Fig. 6, 10 from the back, see Fig. 7, or from the top, see Fig. 8, and extend to the interior of the unit through baffle 10-4a. In the latter case the nozzle ends of the tube are curved to suit.

The heat exchange unit of Fig. 6 is illustrated 15 as particularly adapted for cooling, a drip pan 51 being secured near the base of the unit for catching moisture condensation falling from radiant convector 11.

The air discharge tube heretofore described 20 may be conveniently provided as a self sufficient element complete with individual motor. Such type of air discharge tube is designated 52, Fig. 6, the individual motor being designated 53. With this provision for individual forced supply 25 of air, the air compressor and its appurtenant piping and reservoir may be eliminated from the thermal system.

Speaking generally, both the heat exchange 30 unit and the thermal system of this invention are unique in the art of thermal treatment of air in that a wide range of thermal effects may be readily had with a minimum of spacial encumbrance.

Whereas the invention has been illustrated 35 and described with respect to preferred embodiments thereof, it is to be definitely understood that many changes may be made without departing from the generic spirit and scope of the invention as set forth herein and in the claims that follow.

I claim:

1. A unit heat exchanger comprising radiant convector means having a relatively low thermal conductivity and air flow passages, said radiant convector means being cooperatively associated in direct air flow communication with radiant convector means having a relatively high thermal conductivity and air flow passages, the air flow passages of said radiant convectors being 45 aligned substantially vertically, both of said radiant convector means being provided with passages for confining flow of a thermal fluid in contact with heat exchange walls thereof.

2. A unit heat exchanger comprising radiant convector means formed of cast iron and air flow passages, said radiant convector being cooperatively associated in direct air flow communication with radiant convector means formed of metal, predominantly of copper content and air flow passages, the air flow passages of said radiant convectors being aligned substantially vertically, both of said radiant convector means being provided with passages for confining flow of a thermal fluid in contact with heat exchange walls thereof.

3. A heat exchanger comprising radiant convector means having a relatively low thermal conductivity cooperatively associated with radiant convector means having a relatively high thermal conductivity, the first named means providing a plurality of relatively long, substantially vertical air-flow passages grouped in two sets spaced apart vertically from each other, the respective air-flow passages of one set substantially registering with the respective air-flow

passages of the other set to form stacks extending from the bottom to the top of the heat exchanger, and the last named means being disposed in the space between the said two sets and exposing extensive heat exchange surfaces to 5 air flowing through said stacks.

4. A unit heat exchanger comprising radiant convector means having a relatively low thermal conductivity and air flow passages, said radiant convector means being cooperatively associated 10 in direct air flow communication with radiant convector means having a relatively high thermal conductivity, and air flow passages, the air flow passages of said radiant convectors being aligned substantially vertically, both of said 15 radiant convector means being provided with passages for confining flow of a thermal fluid in contact with heat exchange walls thereof, and structurally independent means for supplying a forced draft of air directly to the last named 20 radiant convector means.

5. A heat exchanger comprising radiant convector means having a relatively low thermal conductivity cooperatively associated with radiant convector means having a relatively high 25 thermal conductivity, the first named means providing a plurality of relatively long, substantially vertical air-flow passages grouped in two sets spaced apart vertically from each other, the respective air-flow passages of one set substantially 30 registering with the respective air-flow passages of the other set to form stacks extending from the bottom to the top of the heat exchanger, and the last named means being disposed in the space between the said two sets and 35 exposing extensive heat exchange surfaces to air flowing through said stacks, and means for supplying a forced draft of air directly to the last named radiant convector means.

6. A heat exchanger comprising radiant convector means having a relatively low thermal conductivity and air flow passages, said radiant convector means being cooperatively associated with radiant convector means having a relatively high thermal conductivity and air flow 45 passages, the air flow passages of said radiant convectors being aligned substantially vertically, both of said radiant convector means being provided with passages for confining flow of a thermal fluid in contact with heat exchange walls 50 thereof, means for supplying a forced draft of air directly to the last named radiant convector means, and Venturi means disposed in the line of flow of air from the radiant convector means for admixing fresh air with the thermally 55 treated air.

7. A heat exchanger comprising radiant convector means having a relatively low thermal conductivity cooperatively associated with radiant convector means having a relatively high thermal conductivity, the first named means providing a plurality of relatively long, substantially vertical air-flow passages grouped in two sets spaced apart vertically from each other, the respective air-flow passages of one set substantially 60 registering with the respective air-flow passages of the other set to form stacks extending from the bottom to the top of the heat exchanger, and the last named means being disposed in the space between the said two sets and 65 exposing extensive heat exchange surfaces to air flowing through said stacks, means for supplying a forced draft of air directly to the last named radiant convector means, and Venturi means disposed in the line of flow of air from 70

75

the radiant convector means for admixing fresh air with the thermally treated air.

8. A heat exchange unit comprising a radiant convector of relatively low thermal conductivity made up of sections whose exteriors are configured to provide lateral concavities extending throughout the lengths of the sections, the said concavities of adjoining units cooperating to form open ended air-flow passages of the nature of stacks extending substantially vertically throughout the height of the unit, said sections being hollow, the hollow interiors of adjoining sections communicating to afford flow of a fluid heating medium through the sections, a peripherally closed aperture intermediately located in and through each section, the apertures of adjoining sections being disposed in mutual registry providing an open passage extending substantially horizontally through the unit transversely of the said air-flow passages, and a radiant convector of high thermal conductivity disposed within said open passage and extending transversely of the said air-flow passages.

9. A heat exchange unit comprising a radiant convector of relatively low thermal conductivity having an open-ended peripherally enclosed passage extending through its body transversely of and intermediate its height, and a plurality of open-ended peripherally enclosed air-flow passages of the nature of stacks extending substantially vertically through its said body intercepting and passing through the first named passage and communicating at their lowermost open ends with air inflow means and at their uppermost open ends with air outflow means; and a radiant convector of relatively high thermal conductivity disposed within said first named passage transversely across said air-flow passages.

10. A heat exchange unit comprising a radiant convector of relatively low thermal conductivity having an open-ended peripherally enclosed passage extending through its body transversely of and intermediate its height, and a plurality of open-ended peripherally enclosed air-flow passages of the nature of stacks extending substantially vertically through its said body intercepting and passing through the first named passage and communicating at their lowermost open

ends with air inflow means and at their uppermost open ends with air outflow means; a radiant convector of relatively high thermal conductivity disposed within said first named passage transversely across said air-flow passages; and Venturi means disposed in the line of flow of air from said radiant convectors for admixing fresh air with the thermally treated air.

11. A heat exchange unit comprising a radiant convector of relatively low thermal conductivity and of box-like contour with substantially plane faces of unbroken continuity for providing panel radiation, said radiant convector having an open-ended peripherally enclosed passage extending through its body transversely of and intermediate its height, and a plurality of open-ended peripherally enclosed air-flow passages of the nature of stacks extending substantially vertically through its said body intercepting and passing through the first named passage and communicating at their lowermost open ends with air inflow means and at their uppermost open ends with air outflow means; and a radiant convector of relatively high thermal conductivity disposed within said first named passage transversely across said air-flow passages.

12. A heat exchange unit comprising a radiant convector of relatively low thermal conductivity and of box-like contour with substantially plane faces of unbroken continuity for providing panel radiation, said radiant convector having an open-ended peripherally enclosed passage extending through its body transversely of and intermediate its height, and a plurality of open-ended peripherally enclosed air-flow passages of the nature of stacks extending substantially vertically through its said body intercepting and passing through the first named passage and communicating at their lowermost open ends with air inflow means and at their uppermost open ends with air outflow means; a radiant convector of relatively high thermal conductivity disposed within said first named passage transversely across said air-flow passages; and Venturi means disposed in the line of flow of air from said radiant convectors for admixing fresh air with the thermally treated air.

EDWARD S. CORNELL, JR.
